CAPACITY CONTROL FOR RECIPROCATING COMPRESSORS

Carlyle M. Ashley, Fayetteville, N. Y., assignor to Carrier Corporation, Syracuse, N. Y., a corporation of Delaware

Application August 22, 1946, Serial No. 692,326
In Argentina September 22, 1947

14 Claims. (Cl. 230—25)

1

This invention relates to reciprocating compressors and more particularly to a system of capacity control for reciprocating compressors.

The chief object of the present invention is to provide a system of capacity control for reciprocating compressors which permits the capacity of a compressor to be adjusted in response to load conditions and which is so designed as to prevent rapid recycling during operation of the compressor.

An object of the invention is to provide a system of capacity control for a reciprocating compressor having a plurality of cylinders which permits complete cylinder unloading by fixed steps to reduce the capacity of the compressor.

A further object is to provide a system of capacity control for a reciprocating compressor in which the compressor cylinders may be unloaded in sequence by holding the suction valve of each cylinder open thereby permitting easy and ready starting of the compressor, permitting the use of normal torque motors for driving the compressor, and enabling variation in the capacity of the cylinder in response to changes in load conditions.

A still further object is to provide a capacity control for a reciprocating compressor in which cylinder unloading is accomplished in response to a change in suction pressure and in which the control may be adjusted or reset in response to variation in room temperature, if desired, to maintain a constant cooler water temperature, a constant relative humidity or dewpoint of conditioned air or the like. Other objects of my invention will be readily perceived from the following description.

This invention relates to a system of capacity control for reciprocating compressors which comprises oil pressure actuated elements for holding compressor valves in inoperative position, oil pressure actuated means for permitting or discontinuing the passage of oil to the elements and means responsive to load conditions for varying the oil pressure imposed on the pressure actuated means to permit or to discontinue the supply of oil to the elements in sequence in accordance with load conditions.

The attached drawing illustrates a preferred embodiment of my invention in which:

Figure 1 is a diagrammatic view illustrating a compressor including the capacity control of the present invention;

Figure 2 is a sectional view illustrating the position of the capacity control within the crank case of the compressor;

Figure 3 is a view partly in elevation and partly

2

in section illustrating means for disposing the suction valve of a cylinder in inoperative position;

Figure 4 is a sectional view of the control valve; and

Figure 5 is a sectional view of the regulating valve.

Referring to the attached drawings, there is illustrated in Figure 1 a compressor 2 having a plurality of cylinders 3, 4, 5 and 6. The compressor may be of any conventional design and includes a crank case 7, the bottom of which serves as an oil sump 8; the operating mechanism includes the usual crank shaft 9, pistons 10, connecting rods 11 and other structural elements normally employed in compressing gas, all of which form no essential part of the invention, but which it will be understood are present to form an operable compressor.

20 It will be appreciated in various applications to which a compressor may be applied there is a need for varying the output responsive to differing or changing load requirements. For this purpose there may be provided suitable unloading mechanism designated generally at 12 adapted to hold the suction valve 13 of a cylinder in inoperative position. Unloading mechanism 12 may be actuated by means of a power element 14 actuated by oil pressure. It will be appreciated mechanism 12 and elements 14 may be provided for any desired number of cylinders of a compressor.

25 A pump 15 is provided for pressure lubrication of moving parts of the compressor. A control valve 16 is connected to pump 15 by a line 17. A relief valve 17' is disposed in line 17 to maintain a constant oil pressure to the moving parts of the compressor and to control valve 16. Control valve 16 is connected to the various power elements 14 by means of lines 18. Control valve 16 serves to permit or to discontinue the supply of oil to each power element 14 in sequence, that is, one after the other as hereinafter described. A regulating valve 19 is connected to control valve 16 by means of line 20 and serves to regulate or adjust control valve 16 as hereinafter described. Regulating valve 19 is connected to the suction manifold of the compressor by a line 21; oil may be drained from valve 19 to sump 8 through line 22.

30 The general arrangement of the capacity control is illustrated in Figure 2. The capacity control preferably is disposed in the pump end cover 23 of compressor 2 and oil is supplied thereto by pump 15 through line 17 to a filter 24. From filter 24 it passes through line 25 to control valve 16.

Oil may be supplied from control valve 16 through lines 18 to the various power elements 14. Valve 16 is connected to valve 19 by line 20. A T 26 is disposed in line 20 and permits passage of oil through line 27 to a suitable gauge 28 adapted to register control oil pressure for the information of the operator.

In Figure 3 there is illustrated suitable mechanism 12 used for disposing the suction valve of a compressor cylinder in inoperative position. It will be appreciated similar mechanism may be provided for each cylinder of the compressor if desired. Mechanism 12 employed to place suction valve 13 in inoperative position consists of lifter sleeve 29, lifter pins 30, loading springs 31 and a retainer ring 32. Preferably, such mechanism comprises a self-contained sub-assembly with the removable cylinder sleeve 33 in which the compressor piston 10 operates. Suction gas from the manifold 34 enters the suction valve port 35 and passes through such port into the interior of the compressor cylinder when valve 13 is moved away from the port 35. When pins 30 are in the position illustrated in Figure 3, the suction valve 13 closes at the end of each suction stroke under the urging of suction valve springs 36. After compression of the gas in the cylinder, the gas is discharged through discharge valve 37 into the cylinder head space 38. Pins 30 remain retracted while full oil pressure is applied to power element 14 and are moved upward to hold valve 13 in inoperative position when oil pressure on element 14 is discontinued, as hereinafter described.

Power element 14 consists of a casing 39 having a base 40 and a top cover 41. A piston 42 is disposed in casing 39 and is connected by a rod 43 to a forked lever 44 operating on a fulcrum 45 disposed at one end of cover 41. The lever 44 terminates in portions 46 adapted to engage the lifter sleeve 29 surrounding the cylinder. A piston spring 47 applies a predetermined pressure to piston 42; in the absence of oil pressure supplied to element 14, piston 42 rests against the bottom cover 40. A vent 48 may be provided in power element 14 to permit oil which seeps past piston 42 to return to the crank case 7 of compressor 2. Preferably, the power elements 14 are located in the suction manifold of the compressor adjacent the cylinder to be unloaded.

When oil pressure is supplied to power element 14, piston 42 moves upward, permitting lever 44 to pivot about fulcrum 45 thus permitting sleeve 29 to be urged downward by springs 31 until such movement is halted by contact of sleeve 29 against ring 32. Downward movement of sleeve 29 carries pins 30 therewith thus permitting suction valve 13 to be disposed in operative position. When pressure is removed from power element 14 as by, for example, discontinuing the passage of oil thereto, piston 42 is forced downward by spring 47, pivoting lever 44 about fulcrum 45 and urging sleeve 29 in an upward direction to raise pins 30, thus holding valve 13 away from port 35. With the suction valve disposed in an open position, no compression of gas takes place in the cylinder and the capacity of the cylinder is zero.

In Figure 4 I have illustrated the control valve 16. Control valve 16 is an oil pressure actuated, multiple port, snap action piston valve. Oil pressure is supplied to a chamber 49 of valve 16 through line 25. A piston 50 is disposed in chamber 49. Piston 50 is provided with a plurality of grooves 51 for a purpose hereinafter described. A spring 52 is held in chamber 49 by a cap 53 and provides a predetermined pressure to urge piston

50 longitudinally of the chamber. The end 54 of piston 50 serves in effect as a partition separating or dividing chamber 49 from a second chamber 55. An opening 56 in end 54 connects chambers 49 and 55. Chamber 55 is connected to regulating valve 19 by line 20.

A plurality of outlets 57 is provided in chamber 49 and are adapted to be connected to lines 18 respectively leading to the various power elements 14. An opening 58 is drilled in the wall or casing of valve 16. A spring 59 is disposed in opening 58 and serves to urge a ball member 60 within one of the grooves 51 in piston 50. Ball member 60 may be loaded with any requisite pressure by means of spring 59.

Regulating valve 19 is shown in Figure 5. Valve 19 includes a chamber 61 in which is disposed a bellows 62. Bellows 62 is subjected on one side to suction pressure through inlet 63. On its opposite side, bellows 62 is subjected to a predetermined force exerted by range adjustment spring 64. The force exerted by spring 64 may be adjusted by means of stem 65 carrying a traveling nut 66. In addition, such side of the bellows is subject to atmospheric pressure.

A port 67 is provided in valve 19 adapted to be closed by a valve member such as a needle 68. A plurality of push rods 69 are provided which convey movement of bellows 62 to member 68. Oil is admitted to the valve through inlet 70 from line 20 connecting the valve with chamber 55 of valve 16. When port 67 is opened by movement of member 68 therefrom, oil is free to flow through the port and through outlet 71 to the crank case of the compressor. An auxiliary spring 72 is provided which operates in opposition to adjustment spring 64 to permit operation in the vacuum range of suction pressure and to lock out the control valve when spring 64 is at its free height.

It will be appreciated the loading imposed on spring 64 may be adjusted to vary the suction pressure at which member 68 tends to move from port 67 to open the valve to the passage of oil. Opening 73 is drilled through the wall of valve 19, such opening being closed by plug 74. Suitable means may be attached to valve 19 through such opening if desired to vary pressure on the outside of the bellows thus varying the loading imposed upon the compressor so that the setting of the control valve may be varied in response to dewpoint temperature, cooler water temperature, room temperature or the like.

In normal operation oil from the lubrication system pump 15 enters the pump end cover 23 through removable filter or strainer 24 as shown in Figure 2. From the strainer 24, oil passes through line 25 to the inlet connection of valve 16. Depending upon the position of piston 50 in chamber 49 certain of the outlets 57 are supplied with oil at full pressure, such oil being conducted by lines 18 to the various power elements 14. Oil in chamber 49 passes through opening 56 into chamber 55 in valve 16. Chamber 55 is connected by means of line 20 to regulating valve 19. If the valve port 67 in valve 19 is open, valve member 68 being moved away from the valve seal, oil is free to pass through port 67 into the crank case through outlet 71 in the wall of valve 19.

Assuming port 67 is open, its effective area is approximately three times as great as the area of the opening 56. When port 67 is open the oil pressure in chamber 55 is reduced to approximately 10% of full oil pressure. When valve member 68 moves to restrict valve port 67 in response to changes in load conditions reflected by

a change in suction pressure, oil pressure in chamber 55 increases; when port 67 is closed completely, oil pressure in chamber 55 increases to the full supply pressure from the lubrication system. As the control oil pressure in chamber 55 varies in response to the movement of valve member 68 in regulating valve 19, piston 50 moves abruptly to open or to close outlets 57 in sequence. The application or removal of oil pressure to the various power elements 14 operates the unloading mechanism 12 to unload or to load the various compressor cylinders.

As an example, assume the compressor is operating at 40 pounds per square inch suction pressure; the range adjustment spring 64 has been previously adjusted so that the moving parts of regulating valve 19 are in equilibrium, with port 67 closed by valve member 68. Under such circumstances, oil pressure in chamber 55 is full supply pressure and piston 50 is at one end of its stroke with all outlets 57 supplied with full oil pressure. The pins 30 of unloading mechanism 12 are retracted and suction valve operation is normal with compressor capacity at its maximum. If the refrigeration load be reduced, the suction pressure tends to decrease permitting valve member 68 to move away from port 67 permitting passage of oil therethrough and decreasing the oil pressure maintained in chamber 55. At an oil pressure value determined by the loadings employed on spring 52 and spring 58 piston 50 will move abruptly to vent one outlet 57 to the crank case 7. Discontinuing oil pressure to one power element operates the unloading mechanism to dispose the suction valve in inoperative position thereby unloading one compressor cylinder. Suction pressure as a result increases to find a new equilibrium condition with the reduced refrigeration load. A further reduction in refrigeration load will again reduce the suction pressure to cause valve member 68 to move a greater distance from port 67 permitting increased flow of oil through the port to the crank case and a further reduction of oil pressure in chamber 55 with a result that piston 50 again moves abruptly to vent a second outlet 57 to the crank case with the result that a second cylinder is unloaded. Additional cylinders are unloaded in sequence, depending upon load conditions. An increase in refrigeration load reverses such operations. The capacity control system provided by the present invention in effect tends to hold the suction pressure substantially constant for wide variations of refrigeration load.

By complete cylinder unloading, capacity reduction is obtained in fixed steps; for example, on a four cylinder compressor, three cylinders may be equipped with the control and the steps of unloading may be 75%, 50% and 25% of full capacity. Such steps, of course, are unequal in relationship to each other since, for example, assuming the compressor has two cylinders unloaded and is balancing itself against a refrigeration load, the unloading of a third cylinder means a 50% reduction in capacity. Refrigeration load changes are gradual and do not match the abrupt increments of compressor capacity. As a result, the suction pressure rises after each reduction in compressor capacity. Unless the pressure differential between the loading and unloading points of each cylinder is great, cyclic operation of the system will occur at intermediate loads. It is normally desirable to hold the suction pressure substantially constant with refrigeration load variation and accordingly it is desirable that

cyclic unloader operation occur. Such operation, however, should not occur rapidly. The present invention prevents rapid cycling at lighter loads despite the increasing magnitude of each step of capacity in relation to the previous step.

Excessive cycling is eliminated in the present system since the control is actuated by a controlled oil pressure obtained by use of a fixed upstream orifice and a regulating valve port and valve member of specific characteristics. In addition, the provision of a control valve actuated by oil pressure permits the snap action ball member to be loaded in such manner that the pressure differential between loading and unloading of any cylinder is large in relationship to the pressure differential between loading or unloading points of successive cylinders. Such practice maintains the over-all system differential small without causing rapid cycling.

If desired, refer to Figure 5, compensated control of compressor capacity may be applied to the system described above to permit automatic resetting of the valve to maintain constant cooler water temperature, constant relative humidity or dew-point of the air or the like. A temperature actuated pneumatic control responsive to room temperature may be connected to valve 19 through opening 13 by the removal of plug 74 thereby varying or changing the pressure imposed upon bellows 62 in accordance with variation in room temperature. Likewise, if desired, an electrical control system may be used to provide compensated control of compressor capacity in place of the pneumatic system described. For this purpose, a control motor equipped with a suitable cam may be mounted on the apparatus so that the cam operates the adjustment stem 65. Operation of the motor in turn may be controlled by any suitable means responsive to room temperature.

The present invention provides accurate control of compressor capacity in response to load conditions. The control system is so designed as to permit ready adjustment thereof merely by employing springs with different characteristics. An advantage of the present invention resides in the fact that the control arrangement may be readily changed or varied without necessitating tearing down the compressor. The entire suction pressure range of operation of the compressor may be readily adjusted by adjusting or changing a simple adjustment spring in the regulating valve. The oil actuated means of the present invention decrease the amount of cycling of the unloading mechanism thus reducing wear on the suction valve and the unloading mechanism while improving the operation of the refrigeration system.

While I have described and illustrated a preferred embodiment of my invention, it will be understood my invention is not limited thereto since it may be otherwise embodied within the scope of the following claims.

I claim:

- 65 1. In a system of capacity control for reciprocating compressors, the combination of an oil pressure actuated element for holding a compressor valve in inoperative position, oil pressure actuated means for permitting or discontinuing the passage of oil to said element, and means responsive to load conditions for varying the oil pressure imposed on the pressure actuated means to permit or to discontinue the passage of oil to said element in accordance with load conditions.
- 70 2. In a system of capacity control for recipro-

cating compressors, the combination of oil pressure actuated elements for holding compressor valves in inoperative position, oil pressure actuated means for permitting or discontinuing the passage of oil to said elements, and means responsive to load conditions for varying the oil pressure imposed on the pressure actuated means to permit or to discontinue the supply of oil to said elements in sequence in accordance with load conditions.

3. In a system of capacity control for reciprocating compressors, the combination of oil pressure actuated elements for holding compressor valves in inoperative position, oil pressure actuated means for permitting or discontinuing the passage of oil to said elements, and means responsive to suction pressure for varying the oil pressure imposed on the pressure actuated means thereby permitting or discontinuing the passage of oil to said elements.

4. In a system of capacity control for reciprocating compressors, the combination of oil pressure actuated elements for holding compressor valves in inoperative position, an oil pressure actuated valve permitting or discontinuing the passage of oil to said elements, and a second valve responsive to load conditions for varying the oil pressure imposed on the first valve to permit or discontinue the supply of oil in sequence to said elements.

5. In a system of capacity control for reciprocating compressors, the combination of oil pressure actuated elements for holding compressor valves in inoperative position, an oil pressure actuated valve adapted to permit the passage of oil to said elements in sequence, and a second valve responsive to load conditions for varying the oil pressure imposed on said first valve whereby said elements are loaded or unloaded in sequence in response to load conditions.

6. In a system of capacity control for reciprocating compressors, the combination of oil pressure actuated elements for holding compressor valves in inoperative position, an oil pressure actuated valve permitting or discontinuing the passage of oil to said elements, and a second valve for varying the oil pressure imposed on the first valve, said first valve including a chamber having a plurality of outlets connected with said elements, a piston movable in said chamber, means for imposing a predetermined pressure on said piston to move it longitudinally in one direction in said chamber, a second chamber having an opening connecting it with the first chamber, oil flowing through said opening into the second chamber, said second chamber being connected to the second valve, said second valve having a port therein closed by a valve member, means for moving said valve member toward or from said port in response to load conditions, said first valve including means for yieldably resisting longitudinal movement of said piston in said chamber, movement of said piston in said first chamber opening or closing the outlets therein to permit or to prevent passage of oil to the elements, oil pressure building up in said second chamber when passage of oil through said second valve is prevented thereby urging intermittent movement of the piston in an opposite direction against the resistance of the holding means to close the outlets to the elements in sequence in accordance with the load conditions.

7. In a system of capacity control for reciprocating compressors, the combination of oil pressure actuated elements for holding compressor

valves in inoperative position, an oil pressure actuated valve permitting or discontinuing the passage of oil to said elements, a second valve responsive to suction pressure for varying the oil pressure imposed on the first valve, said first valve including a chamber adapted to receive oil and having a plurality of outlets therein connected with the elements, a piston movable in said chamber, spring means for imposing a predetermined pressure on said piston to urge it longitudinally in one direction in said chamber, said piston having a plurality of grooves therein, a spring urged ball member disposed within a groove in said piston to resist movement of said piston in said chamber, a second chamber having an opening connecting it to the first chamber, oil flowing through said opening into the second chamber, said second chamber being connected to the second valve, said second valve having a port therein closed by a valve member, means in said second valve for moving the valve member toward or from the port in response to suction pressure, movement of said valve member opening or closing the port to the passage of oil therethrough, closing of said port permitting oil pressure to build up in said second chamber, an increase in oil pressure in said second chamber urging intermittent movement of the piston in an opposite direction against the resistance of said ball member thereby closing the outlets in sequence in accordance with the suction pressure.

8. In a step-by-step capacity control for reciprocating compressors, the combination of members for disposing compressor valves in inoperative position, power elements for actuating said members, an oil pressure actuated valve adapted to permit or to discontinue the passage of oil to said power elements, and a second valve responsive to load conditions for varying the oil pressure imposed on the first valve to permit or to discontinue the passage of oil to said elements in sequence.

9. A step-by-step capacity control according to claim 8 in which the first valve includes a chamber adapted to receive oil having a plurality of outlets thereon connected with the power elements, a piston movable in said chamber, means for imposing a predetermined pressure on said piston to urge it longitudinally in one direction in said chamber, means for yieldably holding the piston against movement in said chamber, a second chamber having an opening connecting it to the first chamber, oil flowing through said opening into the second chamber, the second chamber being connected to the second valve, the second valve having a port therein closed by a valve member, means in said second valve for moving the valve member toward or from the port in response to load conditions, movement of said valve opening or closing the port to the passage of oil therethrough, closing of said port permitting oil pressure to build up in said second chamber, an increase in oil pressure in said second chamber urging intermittent movement of the piston in an opposite direction against the resistance of the holding means thereby closing the outlets in sequence in accordance with load conditions.

10. In combination with a compressor having a plurality of cylinders, a capacity control applied to at least some of the cylinders, said control including means adapted to hold the suction valves of the cylinders in inoperative position, power elements for actuating said means, said power elements being actuated by oil pressure, a

pump for supplying oil to the compressor, a valve actuated by oil pressure serving to govern the supply of oil to said power elements, and a second valve responsive to load conditions for varying the oil pressure imposed on the first valve.

11. In combination with a compressor having a plurality of cylinders, a capacity control applied to at least some of the cylinders, said control including means for disposing at least some of the cylinder suction valves in inoperative position, power elements for actuating said means, a pump for supplying oil to the compressor, an oil pressure actuated valve adapted to regulate the passage of oil to said power elements, and a second valve responsive to suction pressure adapted to vary the oil pressure imposed on the first valve, variation of oil pressure on said first valve loading or unloading the power elements in sequence to control the capacity of the compressor.

12. In a system for varying the output of a compressor, the combination of means for loading or unloading the cylinders of the compressor in sequence in response to load conditions, said means comprising members for disposing at least some of the suction valves of the cylinders in inoperative position, power elements for actuating said members, said power elements being actuated by oil pressure, a first valve governing the supply of oil to said power elements, said valve being actuated by oil pressure, and a second valve adapted to vary the oil pressure imposed upon the first valve whereby power elements are loaded or unloaded in sequence in response to load conditions.

13. A system according to claim 12 in which the first valve includes a chamber having a plurality of outlets connected with the power elements, a piston movable in said chamber, spring means for imposing a predetermined pressure on the piston to urge it longitudinally in one direction in said valve, said piston having a plurality of grooves therein, a spring urged ball member disposed in one of the grooves in said piston to resist movement of said piston, a second chamber having an opening connecting it to the first chamber, oil flowing through the opening into the second chamber, said second chamber being connected to said second valve, said second valve

having a port therein closed by a valve member, means in said second valve responsive to suction pressure for moving the valve member toward or from said port, movement of said valve member opening or closing the port to the passage of oil therethrough, closing of said port permitting oil pressure to build up in said second chamber, an increase in oil pressure in said second chamber urging intermittent movement of the piston in an opposite direction against the resistance of the ball member thereby closing the outlets in sequence to prevent passage of oil to the power elements.

15 14. In a system of capacity control for a reciprocating compressor, the combination of oil pressure actuated elements for holding compressor valves in inoperative position to unload cylinders of the compressor, an oil pressure actuated valve permitting or discontinuing the passage of oil to said elements, and a second valve responsive to load conditions for varying the oil pressure imposed on the first valve to permit or to discontinue the supply of oil in sequence to said elements, said first valve including an oil pressure actuated movable member serving to open or to close outlets to said elements thereby loading or unloading the cylinders of the compressor, and means for yieldably resisting movement of said member, said means being loaded in such manner that the pressure differential between loading and unloading of any cylinder of the compressor is large in relationship to the pressure differential between loading or unloading points of successive cylinders.
